SQUEEZE BOTTLE

Robert N. Marona, Scarsdale, N.Y., assignor to General Foods Corporation, White Plains, N.Y., a corporation of Delaware

Filed Aug. 30, 1965, Ser. No. 86,762

Term of patent 14 years

(Cl. D58—6)

FIG. 1

FIG. 5

FIG. 2

FIG. 3

FIG. 4

FIG. 1 is a top plan view of a squeeze bottle showing my new design;

FIG. 2 is a side elevational view;

FIG. 3 is an end elevational view;

FIG. 4 is a bottom plan view thereof; and

FIG. 5 is a sectional view thereof taken along the line 5—5 of FIG. 2.

The side of the bottle opposite to that shown in FIG. 2 is the same as that shown in FIG. 2.

I claim:

The ornamental design for a squeeze bottle, substantially as shown and described.
